COAT CONSTRUCTION

Hugo Gemignani, Baltimore, Md.

Application May 19, 1938, Serial No. 208,916

2 Claims. (Cl. 2—93)

This invention relates generally to improvements in coat construction; and more particularly, to an expansible bellows-like construction connection in the armhole connection between the sleeves and the body of a coat.

The main object of the invention is to provide at the crotch of the sleeve and body of the coat an expansible construction which will allow the necessary fullness and freedom of movement for the arms of the wearer whenever required, and yet be of such character as to preserve accuracy of fit and symmetry of appearance during the ordinary wear of the garment. Bellows pleats, inserts and other means used heretofore to provide for such freedom of arm movement, inevitably alter the character of the design and finished appearance of the coat, since they are outwardly visible, and therefore limited for use in sports wear.

20 A suitable embodiment of the invention is illustrated in the accompanying drawing, wherein the improvement is shown as incorporated as a crescent-shaped fold in the body of the coat where it connects with the under section or crotch of the sleeve.

In the drawing:

Figure 1 is a fragmentary rear elevation of a coat embodying this invention, with the sleeve raised to show the operation of the improved connection between the sleeves and the body of the coat;

Figure 2 is a fragmentary development of that portion of the body of a coat cut out to receive the end of the sleeve, and showing the body of the coat as entirely laid out;

Figure 3 is a similar view of the parts shown in Figure 2, but with the crescent-shaped fold formed in the crotch thereof and in position to be sewn to the sleeve of a coat;

40 Figure 4 is a fragmentary section showing the method of attaching the sleeve of a coat to the crescent-shaped fold aforesaid, and also the lining construction as employed in this coat; and

Figure 5 is a fragmentary development of the coat and sleeve linings at crotch parts thereof.

Referring to Figure 1 of the drawing, the reference numerals 5, 6 and 7 designate, respectively, the back and sleeves of a coat constructed in accordance with the present invention. The 50 crescent-shaped folds 8 and 9 are formed on those parts of the coat connected to the sleeves in the crotches between the sleeves and the coat. These folds are formed in such manner as to eliminate the pull between the elbows and shoulders of the 55 coat and to prevent the back from riding up when

the arms are raised substantially as shown in Figure 1. The joints in the crotch between the sleeve and body of the coat are somewhat elastic. This elasticity in the joint and freedom of movement on the body of the wearer is secured by 5 forming the crotch between sleeve and coat in the manner indicated in Figures 2, 3 and 4 of the drawing.

Figure 2 of the drawing shows front, back and side portions 10, 11 and 12 of the coat united in the usual manner to form one of the shoulder portions of the coat body. The upper end of this portion is first cut along the curved outline 13 to form one armhole. The dotted curved line 14 merging with the curved line 13 between the 15 points 15 and 16 would indicate the seam edge of the armhole line of a coat of standard construction, and in the present instance, indicates the crease formed by the crescent-shaped expansible fold 9 used to form the crotch of the coat. 20 In the finished coat the curved parts 13 above the points 15 and 16 appear as a stitched seam in continuation of a crease 14 formed in the body of the coat. When the arms are in normal position this crease and the line of stitching give the same 25 appearance to the improved coat as is present in a coat of conventional construction.

Figure 3 of the drawing illustrates the parts shown in Figure 2 with the crescent-shaped fold 9 formed in the crotch of the armhole. In this 30 final form of the coat body, the upper parts of the coat body between the points 15 and 16 have been folded around the crease line 14 and have been pressed flat against the body part of the coat. It will be observed that the part of the curve 13 35 lying between the points 15 and 16 is considerably stretched during the operation of folding around the crease line 14. This folding and stretching is effected by dampening the cloth adjacent the fold and ironing the crescent-like section 9 about the 40 crease line 14 while maintaining the other parts of the armhole substantially in the position shown in Figure 2. In folding the crescent-like section 9 in this manner, the cloth along the line 13 between the points 15 and 16 becomes stretched to 45 form the longer line or edge 13', while the cloth along the crease line 14 becomes somewhat compressed. After this operation, the crescent-shaped part 9 is somewhat elastic in its lengthwise direction.

The sleeve 7 at its upper end is sewn in the usual manner to the coat body along the lines 13 above the points 15 and 16. The crotch part of the sleeve between the points 15 and 16 is sewn to the lower edge 13' of the crescent-shaped section 55

9. It will be understood, of course, that sufficient cloth will be allowed to permit the formation of the seams along the lines of stitching indicated on the drawing. This operation completes the construction of one sleeve element of the coat shown in Figure 1 of the drawing. Obviously, the other sleeve 6 will be similarly connected to the coat body.

The sleeve construction described not only provides for an elastic expansible connection at the sleeve crotches of a coat, but, by its formation, also eliminates the necessity of taping the body of the coat around the crotch in order to prevent stretching thereof. In fact, the tape in this construction must be omitted around the crotch part of the armhole where the expansible connection is made in order to present the elasticity or lengthwise strength of the crotch in a manner which distinguishes the present invention from everything preceding it.

By reserving the armhole at the crotch, the possibility of binding or pressure on the part of the seamed material against the bottom and rear of the arms is eliminated. Since the pit of the armhole in this construction is a crease instead of a stitched seam, the armhole may be cut higher on the garment, thereby adding to the length of the back and sleeve section with consequent added comfort to the wearer and without causing unsightly wrinkles.

The coat construction just described requires a corresponding modification of the lining. As shown in Figures 4 and 5, the body lining 17 is cut out at the armhole to form a normal seam

line 18 directly opposite the crease line 14 and the stitched continuations 13 thereof. Since the lining material is ordinarily non-stretchable, it is necessary to use a crescent-shaped insert 19 in the crotch connection between the body lining 17 and the sleeve lining 20. This insert 19 overlies the correspondingly crescent-shaped fold 9 between the body and sleeve of the coat proper, the armhole crotch of the lining being formed by a stitched seam instead of a crease.

What I claim is:

1. In a coat, a body portion cut to form an armhole and creased at the lower part of the armhole to form a crescent-shaped, outwardly directed fold integral with said body portion and with its widest part extending downwardly toward the back of said body portion, and a sleeve stitched to the free edge of said fold and to the curved edges of the armhole extending from the opposite ends of the crease formed by said fold.

2. In a coat, a body portion cut to form an armhole and creased at the lower part of the armhole to form a crescent-shaped, outwardly directed fold integral with said body portion and with its widest part extending downwardly toward the back of said body portion, and a sleeve stitched to the free edge of said fold and to the curved edges of the armhole, extending from the opposite ends of the crease formed by said fold, said crease forming a smooth continuation of the stitched part of the seam between the sleeve and body portion and extending around the shoulder from said opposite ends.

HUGO GEMIGNANI.
